(57) **CLAIM**

The ornamental design for an ice bucket set, as shown and described.

DESCRIPTION

FIG. 1 is a front perspective view of an ice bucket of the present embodiment;

FIG. 2 is a bottom perspective view thereof;

FIG. 3 is a front perspective, exploded view thereof;

FIG. 4 is a cross section view, thereof;

FIG. 5 is a front orthographic view, with the rear view a mirror image thereof;

FIG. 6 is a right orthographic view, with the left side view a mirror image thereof, showing the cross section 4-4;

FIG. 7 is a top orthographic view thereof;

FIG. 8 is a bottom orthographic view thereof;

FIG. 9 is a front perspective view of a first iteration of an ice bucket of the present embodiment;

FIG. 10 is a bottom perspective view thereof;

FIG. 11 is a front perspective, exploded view thereof;

FIG. 12 is a cross section view, thereof;

FIG. 13 is a front orthographic view, with the rear view a mirror image thereof;

FIG. 14 is a right orthographic view, with the left side view a mirror image thereof, showing the cross section 12-12;

FIG. 15 is a top orthographic view thereof;

FIG. 16 is a bottom orthographic view thereof;

FIG. 17 is a front perspective view of a second iteration of an ice bucket of the present embodiment;

FIG. 18 is a bottom perspective view thereof;

FIG. 19 is a front perspective, exploded view thereof;

FIG. 20 is a cross section view, thereof;

FIG. 21 is a front orthographic view, with the rear view a mirror image thereof;

FIG. 22 is a right orthographic view, with the left side view a mirror image thereof, showing the cross section 20-20;

FIG. 23 is a top orthographic view thereof; and,

FIG. 24 is a bottom orthographic view thereof.

The portions shown in broken lines are for illustrative purposes only, and form no part of the claimed design.
